UNITED STATES PATENT OFFICE.

ALBERT CHOPARD, OF MOUTIER-GRANDVAL, SWITZERLAND, ASSIGNOR TO
THE SOCIÉTÉ INDUSTRIELLE MOUTIER-GRANDVAL, OF SAME PLACE.

STEM-WINDING WATCH.

SPECIFICATION forming part of Letters Patent No. 317,627, dated May 12, 1885.

Application filed August 7, 1884. (No model.)

To all whom it may concern:

Be it known that I, ALBERT CHOPARD, of Moutier-Grandval, Switzerland, have invented an Improvement in Stem-Winding Watches, 5 of which the following is a specification.

My invention relates to the construction of the rocker-plate and connected parts.

In the drawings, Figure 1 represents an elevation of the stem winding and setting mechanism with the parts in position for winding up the watch. Fig. 2 is an elevation with the parts in position for setting the hands, and Fig. 3 is a section of the rocker-plate and wheels connected with it.

15 The rocker A is pivoted upon a boss, f, projecting from the plate L, by means of the screw d, and this screw while keeping the rocker in place also forms the pivot upon which said rocker can be moved. The rocker carries the 20 wheel E, connected to it by and turning upon the screw i, and this wheel E is between the rocker and the plate L, and is always in gear with a wheel, D, that is also between the rocker and plate L. The wheel D has the boss f for 25 its center of motion; but if the wheel revolved upon this boss said boss would soon become worn in consequence of its being part of the plate L, which is of comparatively soft metal, such as brass. I therefore place a ring of steel, 30 e, around the boss f, and secure it in place by the pin or screw h, and upon this steel ring the wheel D revolves. The wheel D gears with the crown-wheel M upon the winding and set-

ting stem, which latter is provided with a crown, as usual. The rocker A is made with 35 four arms, a, b, c, and g. The arm g has a convex portion, against which the spring B rests. The arm c has an inclined end, against which the end of the lever C acts, and the arms a and b limit the movement of the rocker by 40 coming in contact with the sides of the circular recess occupied by the wheel E and that portion of the rocker having the arms a and b. The spring B keeps the rocker A in the position shown in Fig. 1, with the wheel E in gear 45 with the wheel F of the spring-barrel, the arm a limiting the movement of the rocker. When the rocker is moved by the lever C to the position shown in Fig. 2, the arm b limits the movement of the rocker, and the wheel E is 50 brought into gear with the wheel G, for setting the hands through the medium of the pinions J H and wheel K.

I claim as my invention—

In a stem-winding watch, the combination, 55 with the rocker A and the plate L, having a boss, f, of the wheel E and pivot i upon said rocker, the steel ring e, around the boss f and secured to the plate L, and the wheel D, revolving upon such steel ring, substantially as 60 specified.

ALBERT CHOPARD.
